UNITED STATES PATENT OFFICE.

JAMES RANDOLPH GREENWOOD BRIERCLIFFE AND GEORGE CHISNALL, OF FARNWORTH, ENGLAND.

CLEARER FOR SPINNING-MACHINES.

1,246,535.

Specification of Letters Patent. Patented Nov. 13, 1917.

Application filed January 18, 1916. Serial No. 72,838.

To all whom it may concern:

Be it known that we, JAMES RANDOLPH GREENWOOD BRIERCLIFFE and GEORGE CHISNALL, subjects of the King of Great Britain, and residents of Farnworth S. O., in the county of Lancaster, England, have invented a certain new and useful Improvement in Clearers for Spinning-Machines, of which the following description, having reference 10 to the accompanying sheets of drawings, is a specification.

Our invention relates to improvements in or appertaining to clearers for the rollers of preparing, spinning and like machines 15 of the type in which a board is reciprocated over the surfaces of the rollers to be cleaned, and our present improvement consists in means for giving such traverse to said board by separate mechanism or by combining a 20 rotary and an oscillatory clearer whereby the rotary part reciprocates the other portion.

Figure 1 is a sectional end elevation of the rollers of a drawing frame, showing the 25 application of our improved clearers to the upper rollers thereof.

Fig. 2 is a plan of parts shown by Fig. 1.

Fig. 3 is a similar view to Fig. 1 and illustrates our improvements applied to the lower 30 rollers of the machine.

Fig. 4 is a plan of the parts shown by Fig. 3, except that the upper rolls are omitted from Fig. 4.

Fig. 5 is an end elevation showing another 35 modified form of our invention.

Fig. 6 is a similar view to Fig. 3, illustrating a further modification of our improvements.

Fig. 7 is a plan of the combined clearer 40 illustrated by Fig. 6.

Fig. 8 is a sectional end elevation of the rollers of a spinning machine having our improvements applied to the lower series thereof.

Fig. 9 is a plan of the improved combined clearer illustrated by Fig. 8.

Similar letters and figures of reference indicate like parts throughout the several views.

In all the drawings above referred to 50 certain parts of the framework supporting the drawing and spinning rollers are omitted for the sake of clearness. A indicates the upper series of drawing or spinning rollers and B the lower series thereof.

In carrying our invention into effect we arrange a roller *a* (which preferably has its surface covered with flannel or similar substance) to rest by gravity, or to be slightly pressed by being weighted or by 60 springs, upon the surfaces of the two rear rollers of the upper series A, while as said rollers A are rotated in the direction indicated by the arrows, said covered roller *a* will be rotated and will clean the surfaces 65 of said rear rollers. Resting upon the surfaces of the two front rollers of the series A we have a board *b* with its lower surface faced with flannel or the like, and to this board *b* are attached uprights *b*¹ at each 70 side thereof, these uprights *b*¹ lying in the path of motion of the pegs or crank pins *c* mounted at each end of the clearer *a*. It will be seen that as the clearer *a* is rotated by frictional contact as above described, the 75 crank pins *c* will move the uprights *b*¹ and so traverse the clearer *b* over the upper surfaces of the series of rollers A, thus to clean said surfaces or remove therefrom any dirt or objectionable matter, said uprights *b*¹ 80 being pressed against the crank pins *c* throughout the extent of the rotary movements of the latter by the friction of the rollers A against the lower surface of the clearer *b*, while the rear edge *b*² of said 85 clearer *b* will assist in cleaning or clearing the surface of the roller A¹ during the time that same is resting in contact therewith.

The downwardly projecting lips *b*³ at the front of the clearer *b* limit the rearward 90 movement of said clearer, by which means the crank pins *c* may traverse through a portion of their rotary movements without operating said clearer *b*, and in order that the extent of the movement of the latter 95 may be varied, we may arrange the uprights *b*¹ to be adjustable relatively to the other parts of the clearer. The lateral movement of the clearer *b* is controlled or prevented by the edges *b*³ taking over the ends of the 100 fluted parts of the rollers A or upon the reduced portions A² of said rollers A. Flanges *a*¹ are also arranged on the clearer *a* for the same purpose.

We find, in cases where the clearer *a* is rotated by resting on the surfaces of the rollers A by gravity, that when in the position indicated by Fig. 1, the frictional contact thereof is not great enough to perform the reciprocation of the clearer *b* against the fric- 105 110

tional contact of its lower surface upon the front rollers A, and to overcome this, we embed in the clearer *a* plugs or weights of lead or the like *a*² these plugs being arranged eccentrically relatively to the axis of the clearer *a*, such plugs *a*² increasing the grip of the surface of said clearer *a* upon said rollers A. The exposed ends of the plugs are flush with the surface of the rolls. 10 We preferably make use of a handle *o* by which the clearer *b* may be moved, and by forming same hollow and placing therein different amounts of granulated or like substances such as shot, we may vary the friction between the surface of the clearer *b* and the rollers A. We can at any time during the operations of the machine remove the clearers *a* and *b* separately for the purpose of cleaning or repairs. 15 In Figs. 3 and 4 we have shown a combined revolving and reciprocating clearer for the lower rollers, the rotary portion *a* driving or reciprocating the other part *b* in a manner somewhat similar to that hereinbefore described. The clearer *a* is supported in frictional contact with the two rear rollers of the series B by means of the weights *d* and cords *d*¹, the latter of which pass over reduced portions of the roller B². 20 The clearer *b* is supported by the weights *f* and cords *f*¹, the latter of which take over reduced portions of the roller B³. On the ends of the clearer *a* we form or mount cams or scrolls *a*³ which make contact with and operate the projecting parts *b*⁴ mounted or formed upon the clearer *b*, said parts *b*⁴ being pressed against the cams *a*³ by the frictional contact of the surfaces of the two front rollers B with that of the clearer *b*. 25 The roller B³ is usually smaller in diameter than the other rollers of the same series, hence we form a raised part *b*⁵ on the clearer *b* to make contact therewith.

Fig. 5 illustrates a slight modification of the means for reciprocating the clearer shown by Figs. 3 and 4, in this case eccentrics *a*⁴ being employed instead of the cams *a*³. In Fig. 6 crank pins *a*⁵ are made use of and these in their rotations operate links *g* which are connected by the pins *g*¹ to the clearer *b*, the reciprocations of said clearer *b* being similar to those hereinafter described. In connection with these under clearers, the rear end thereof assists in cleaning the surface of the rollers B² in a similar manner to the cleaning of the roller A¹ by the top clearer *b* shown in Fig. 1. The clearer *a* in Fig. 6 is supported by weights *a*² and cords

*d*³, the cords passing over reduced portions of the roller B² and being attached to 60 links *g*.

In Fig. 8 the clearer *a* has crank pins *a*⁵ fixed in its ends, these being connected to the clearer *b* by means of the eye bolts *a*⁶, in order that the clearer *a* will by its rotations, 65 reciprocate the clearer *b* over the surface of the front roller B. In this case, we have the clearers *a* and *b* positively connected together, so that the weights *f* and cords *f*¹ will support both the said clearers *a* and *b*, 70 while the latter is positively operated or moved over the rollers B in both directions.

Such being the nature of our said invention, what we claim is:—

1. In connection with the rollers of spinning machines, a clearer roller for contact with certain of said rollers, a reciprocatory clearer for contact with the surfaces of said rollers, and a connection between the two clearers whereby the rotating clearer drives 80 the reciprocatory clearer.

2. In connection with the rollers of spinning machines, a rotary clearer for contact with certain of said rollers, a reciprocatory clearer for contact with certain other rollers, and a device intervening between the two parts whereby the reciprocatory clearer is traversed in one direction by the rotary clearer and in the opposite direction by the friction of the spinning or like rollers. 90

3. In connection with spinning machines, a rotary clearer for contact with certain of the rollers, a reciprocatory clearer for contact with certain other rollers, a connection between the two clearers, and means whereby the traverse of the reciprocatory clearer is regulated. 95

4. In connection with the rollers of spinning machines, a rotary clearer for contact with certain of the rollers, a reciprocatory clearer for contact with certain other rollers, and a connection between the two clearers whereby the reciprocatory clearer is driven positively in both directions by the rotary clearer. 100

5. In connection with the rollers of spinning machines, a rotary clearer resting by gravity upon and being rotated by certain of said rollers, a reciprocatory clearer resting upon certain other rollers, a connection 110 between said rotary and reciprocatory clearers, and means for weighting said rotary clearer.

JAMES RANDOLPH
GREENWOOD BRIERCLIFFE.
GEORGE CHISNALL.
